**APPARATUS FOR THE MAGNETIC RECORDING
OF DATA**

Stephen H. Blackford, Endicott, N.Y., assignor to International Business Machines Corporation, New York, N.Y., a corporation of New York

Application August 13, 1956, Serial No. 603,551

11 Claims. (Cl. 340—174)

The invention relates to storage devices and more particularly to magnetic data storage devices capable of storing large quantities of data wherein direct access to each individual record of stored information can be obtained and each individual record can be recorded with a minimum amount of lost time.

In computers, data processing machines or the like, it is quite common to store data in magnetic recording tracks of magnetic drums or in magnetic tapes. The stored data is usually removed in some predetermined sequence for processing and the desired information is then either returned to a specified storage location or directed to a suitable output device. In most installations information is recorded sequentially and operated upon in some predetermined manner as it is sequentially read from the drum or tape. However, there are some accounting installations wherein it is necessary to have available for processing, records which do not follow serially in sequence nor is it economically feasible to store the records in this manner because the desired data or demands will vary widely from operation to operation and day to day.

Under the normal tape installation, it may be necessary to reel and unreel large quantities or lengths of magnetic tape to seek and find one record. This, of course, may cause the computer to stand idle, waiting for the record, and consume a prohibitive amount of processing time.

L. D. Stevens et al. application, Serial No. 477,468, filed December 24, 1954, and assigned to the assignee of the present invention, discloses a means for overcoming the above objection by providing random or multiple access to any record in a magnetic disk storage unit or file. This is accomplished by providing a plurality of axially spaced disks which are mounted on a rotatable shaft for rotation in unison. Each disk includes two flat oppositely directed faces or surfaces having magnetic material thereon to provide a plurality of spaced circular data storing tracks or paths. The digit positions from track to track are substantially radially aligned to provide substantially identical start, read or write positions at the beginning and end of each group of data on each track.

Since each track and disk face is numbered, any track in the storage device may be individually addressed. One or more read/write heads or transducers can be moved to each disk and radially along the faces to any track thereon under the control of an address instruction which has previously been placed in a suitable register or the like. Since a record of a customer, along with all the required information, may be combined into words of data bearing digits and placed in a group on a single track for storage, it can be seen that with the proper instruction any record may be rapidly made available for processing. The only major delay is the time required to move the transducer or read/write head to the location desired. With certain accounting operations involving a large number of individual transactions scattered over the entire storage unit and which do not occur in a pre-

2

determined serial sequence, this represents a vast reduction in computer idle time.

While the above access memory device represents a large reduction in access time, it is still necessary during a reading and writing instruction to delay both operations until the aligned fixed data position on the disk approaches or reaches the read/write heads or transducers. A timing signal or the like must also be provided in synchronism with the disk rotation to initiate the desired reading or recording of the data. Thus during either reading or writing, operation is prevented until the control signal is generated at some particular portion of a drum revolution. Under these conditions, a loss of time, in addition to that required to place the read/write head at the desired track, will occur on practically each read/write operation and this averages approximately one-half the time it takes for one revolution of the disk.

The above random access magnetic memory unit combined with a computer makes available an efficient in-line data processing machine. The in-line data method of data processing maintains the records in business continuously up to date. Any transaction affecting a business may be processed when the change occurs, and all records and accounts affected can be up-dated immediately. Thus information is available at any time with respect to the status of any account at that moment.

A plurality of random access magnetic storage units are provided wherein data are stored in circular tracks or paths on the faces of a plurality of constantly rotating disks. Each unit includes 100 disk faces with 100 tracks per face. Thus 10,000 tracks of storage are provided per unit, or 100,000 tracks would be available in a ten unit system. Each unit has the capacity of storing 6,000,000 digits of data or 600,000 words of ten digits each with sixty words stored as a group on each track. Since from one to ten units are contemplated, 60,000,000 digits or 6,000,000 words of data are available for processing with a time interval which varies from approximately fifty milliseconds up to a maximum of 800 milliseconds after a seek instruction, the average access time being approximately 500 milliseconds. A complete revolution of the disks requires approximately fifty milliseconds. Thus after the selected read/write transducer reaches the desired track, the operation must normally wait an average of twenty-five milliseconds before either a read or write operation can be initiated if a fixed digit or starting location on the track is considered.

Under the above conditions, it can be seen that when processing large quantities of data selected at random locations in the storage units, any reduction in data manipulation time has considerable value. If a more rapid reading and writing can be accomplished, the time saved can be made available for further or additional data processing.

The present invention is directed to a method and means for decreasing the time required for recording or writing in a random access data storage device by eliminating the time delay after a specified access arm and read/write head is placed at the selected track. As soon as the selected transducer is properly located at the desired track, a write operation can be immediately initiated, regardless of the circumferential orientation of the previously recorded data on the selected track or any other track. The recording operation is initiated by an erase phase in which any data passing under the transducer is erased or removed. After a predetermined length of the track has been erased, corresponding to a predetermined number of words or digits, a gap or space end signal is generated, after which the data, arranged as a group of words, is delivered from a buffer storage device

and recorded on the track serial by bit, digit and word. As the latter portion of the word group is delivered, this data overlaps and is recorded in the initial portion of the previously erased section on the track. The last bit written in the word group indicates the end of that particular record, and it is physically located along the circumference of the track at a suitable distance from the initially recorded end of gap signal on the same track. This provides a signal-free gap between the last digit and first recorded digit which is approximately two words in length, depending upon various operating condition. This interval is sufficient to permit the read amplifiers and other circuitry to settle and be in condition to initiate a read operation upon the arrival of the previously generated end of gap pulse at the read/write heads.

From the above, it can be seen that recording on any track may be accomplished at random after the selected transducer is properly positioned without waiting for a synchronization signal or the like which is timed to appear at some specific point in the disk revolution. Also when a plurality of heads are utilized, they may be circumferentially positioned at any suitable location.

The above random recording results in a saving in time on each recording operation varying from 0 to 1 disk revolutions. Under the conditions, this represents approximately fifty milliseconds for each revolution.

The recording of data occurs at random for each recording and varies from track to track, disk face to disk face and unit to unit without regard to any particular synchronization or home pulse location.

The reading of data from any track must await the generated end of gap signal provided on the selected track.

It is one of the objects of the invention to provide a high capacity storage device with an improved recording operation cycle which provides an average reduction in the time required for recording data.

It is another object of the invention to provide a data storage device with an improved recording operation cycle which provides for rapid recording and then checking of the recorded data.

It is yet another object of the invention to provide a random access storage device having a record storing circular track which stores a data record written at random along the track.

It is still another object of the invention to provide a random access storage device having circular digit storing tracks in which corresponding digit positions of the recorded data may be circumferentially displaced from track to track.

It is another object of the invention to provide a random access storage device having data storing tracks in which synchronization of some point in the storage device and the delivered data to be recorded has been eliminated.

It is another object of the invention to provide a multitracked random access magnetic storage device for storing a word group in a track which permits the location of the word group on a track to vary with respect to word groups on other tracks.

It is still another object of the invention to provide a random access magnetic storage device which has a separate start of record indication for each track.

It is yet another object of the invention to provide a random magnetic storage having data storing tracks with a plurality of access arms which may be concurrently directed to different tracks for consecutive reading or writing operations.

It is another object of the invention to provide a random access magnetic disk type storage device for the random storing of word groups on a plurality of data storing tracks which have no specific circumferential location for receiving the initial digits of the word group during a recording operation.

It is yet another object of the invention to provide a

random access magnetic disk type data storage device which erases a portion of the track prior to the delivery of the data to be recorded.

It is still another object of the invention to provide a random access magnetic disk type storage device having a plurality of data storing tracks in which a space is provided between the last and first bit positions recorded on a track.

It is yet another object of the invention to provide a random access magnetic storage unit having rotating data storing tracks which eliminates the synchronizing pulse generating means normally associated with a precise location on the rotating tracks.

Other objects of the invention will be pointed out in the following description and claims and illustrated in the accompanying drawings, which disclose, by way of examples, the principle of the invention and the best mode, which has been contemplated, of applying that principle.

In the drawings:

Fig. 1 is a block diagram of a data processing system incorporating a small capacity intermediate buffer storage device and a plurality of large capacity random access magnetic storage units to which the improved recording operation is applicable.

Figs. 2a and 2b, with 2a disposed above 2b, diagrammatically represent the calculator distributor along with circuitry for receiving and transferring the distributor information into current conducting circuits for selectively operating access arms of random access units and for selecting a particular read/write head to be used in the read or write operation.

Fig. 3 is a diagrammatic view of a servomechanism for selectively positioning a related access arm at the desired disk and track location in accordance with the instruction in the register.

Figs. 4a to 4d schematically represent in block diagrams a method of reading and writing a record on a selected track of a random access memory unit.

Fig. 5 is a diagrammatic isometric view of a plurality of disks forming part of a random access data storage file unit.

Fig. 6 is a top plan view of one of the disks diagrammatically showing some of the circular data storing tracks or paths.

Fig. 7 is a diagrammatic showing of one bit position of a core storage device which is incorporated in the immediate or buffer storage unit shown in Figs. 1 and 4.

Fig. 8 is a block diagram of a group of sixty words which represent the data stored on a single track.

Fig. 9 is a block diagram of a single ten digit word of data plus sign.

Fig. 10 is a block diagram of a ten digit instruction word used in the processing of the data words.

Fig. 11 is a block diagram representation of an instruction word for a random access storage address.

Figs. 12 and 13 show the bit lines for transferring data, parallel by bit and serial by bit, respectively.

Fig. 14 is a developed view of a flux pattern representing data stored along one of the tracks.

Fig. 15 is a developed view of the beginning of a recording operation along one of the tracks.

Fig. 16 is similar to Fig. 15 but shows the end of the recording operation along the same track.

Fig. 17 is a diagrammatic development of a recording operation.

Fig. 18 is a timing diagram of the serial reading of data from a data track along with certain of the required timing pulses for the reading and writing operation.

Figs. 19 and 20 show, respectively, how the ten decimal digits are represented in biquinary and 2-out-of-5 codes, respectively.

Fig. 21 shows the sheet layout of Figs. 4a to 4d, inclusive.

Tubes and control switches

In each of the drawings of the various control devices, the individual components or units making up that device are indicated merely as a box or block. The specific circuitry of such blocks will not be generally described as applied to various typical forms of tubes and diode circuits. A detailed description of necessary typical diode coincident switches, diode mixers, inverters, single and double latches, along with cathode followers and power tubes, where required, and which would be applicable or necessary to apparatus of this type is shown and described in F. E. Hamilton et al. application, Serial No. 544,520, filed November 5, 1955, and assigned to the assignee of the present invention. In fact, the disclosed embodiment is applicable to the data processing unit disclosed in the Hamilton et al. application.

For the purpose of this description, a typical coincident switch, shown as a triangle, otherwise known as a logical And circuit or diode switch, comprises diodes or the like, not shown, each including an individual input terminal normally biased negative so that the common terminal is at a negative potential with respect to ground. If coincident positive pulses are applied to all input terminals, the potential of the output terminal is raised. However, if only one of the input terminals is pulsed positively, the potential of the common output terminal is not raised appreciably. Any voltage responsive device may be controlled by the potential of the output terminal to furnish a usable output voltage level whenever a coincidence of positive input pulses is detected.

A typical mixer, otherwise known as a logical Or circuit or diode mix, may also comprise diodes or the like. In the present drawings to distinguish diode mixers from diode switches, the former is shown as an arc of a circle. Any suitable voltage responsive device is controlled by the potential of the common output terminal of the diode mix. This terminal is connected by a suitable resistor to a negative voltage source, not shown, and maintains a negative bias in the related grid of the tubes. Each diode is connected to an individual input terminal which in turn is connected in the electrical circuit. If either one or all of the diode input terminals is pulsed positively, the potential of the output terminal is raised, which permits the tube associated therewith to conduct or operate in a predetermined manner.

Hereinafter in the specification wherein a conductor or circuit terminal or the like is referred to as being positive or negative in potential, this does not necessarily mean that the point in question is positive or negative in an absolute sense but more positive or more negative relative to its previous state. This principle also applies to any description wherein positive or negative pulses are mentioned or referred to as up or down, or raised or lowered.

While cathode followers or the like are not shown, it is to be understood that various types may be utilized in different locations and the circuits may involve various resistance values and capacity couplings to produce the desired outputs. Since the particular cathode followers used are not part of the invention, a detailed description of each possible type is not deemed necessary. Likewise, in the drawings all power tubes, inverters, double inverters, and the like which would normally be required to maintain the proper signal level have, for the purposes of simplicity, been eliminated. The type and number and particular location would depend upon the results desired. Also for the sake of simplicity, details of the necessary driving rings, single and double latches have been eliminated. Generally, a single latch comprises a double inverter and cathode follower which responds to an input signal to raise the output of the cathode follower, which in turn supplies the desired signal and has a feed-back leading to the input to maintain the cathode follower conducting. The latch is turned Off by interrupting

the latch back signal. A more detailed explanation is provided in the above Hamilton et al. application, and apparatus of this type is shown and claimed in E. S. Hughes, Jr., Patent 2,628,309, issued February 10, 1953.

5 In Figs. 1, 2a-2b, and 4a-4d, a series of single connecting lines are shown leading to and from the various blocks. It is to be understood that the major portion of these single lines actually embody a plurality of lines and that single lines are shown as a means for simplifying the drawings. The heavy shaded lines represent the data transmission lines between the blocks while the lighter shaded lines are primarily control lines for selectively directing the data from one location to another.

15

General description

Referring to Fig. 1, there is disclosed a data processing machine or calculator 21 which is provided with a magnetic drum or the like 22 for storing a quantity of data as magnetized spots on the surface. A program storage device or register 23 is provided for storing a single program step or instruction word 24, Fig. 10.

20 The program or instruction word 24, Fig. 10, comprises ten digits which are divided into three portions: a four-digit address portion 25, D8-D5, for instructing the machine where data to be processed is located in the storage 22; a two-digit operation portion 26, D10-D9, for instructing the machine what operation or process the machine is to perform with the data found in the address portion; and a four-digit instruction address portion 27, D4-D1, for instructing the machine where the next program step is located in storage.

25 An address register 28, Fig. 1, and an operation register 29 are provided for receiving the address portion 25 and the operation portion 26, respectively, from the program register 23. Switching circuitry 31 is provided under the control of the address register for selecting any storage position on the drum 22 or other available storage device on the machine in accordance with the value stored in the address register 28. The switching circuitry 31 is also under control of the operation register 29 for determining the operation the machine is to perform on the data found at a selected address position. After an address is selected and the data found at the address is operated upon by the machine, the instruction 30 address portion 27, Fig. 10, of the program word is entered into the address register 28, Fig. 1, from program storage 23 to replace the value previously in the register. A new program step located at the address in storage corresponding to the instruction address portion 27 of the program step in the address register is selected and transferred into the program storage device 23 to replace the value previously stored therein. Thus large numbers of program values and considerable amounts of data may be stored on the magnetic drum 22 and the sequence of the above-outlined procedure may automatically continue for a large number of program steps.

35 An accumulator 32, an adder 33, and a distributor 34 are also provided in the machine as well as circuitry for introducing machine developed values to be adder. The machine is provided to handle a plurality of digits grouped to define a word of data. As shown in Fig. 9, the word of data or operand 35 consists of ten digits and an algebraic sign. The words are stored serially on the drum 22, Fig. 1, and the digits of a word are stored serially within each word interval. Digits are represented by parallel combinations of magnetically stored bits, as shown in Fig. 12. Information is thus said to be stored parallel by bit, serial by digit and word. While various coding systems may be devised, in this particular embodiment the arithmetic units use a biquinary system, as shown in Fig. 19, where the presence of two of seven possible parallel stored bits determines the digits decimal value.

40 75 In the stored programming system used by this ma-

chine, each instruction (program step) is stored in a word storage location as a ten digit word, Fig. 10. The coded digits of an instruction word, when interpreted by the program control circuits give information as to what operation is to be performed, in which storage location to find the data to be used in performing the operation and in which storage location the next ten digit instruction word is to be found. A stored sequence of such instruction words forms a program routine.

Calculations are performed by electronic means. All 10 arithmetical and logical operations are built into the machine. They are activated by the operation code portion 26 of the instruction word 24, Fig. 10. The arithmetic units of the machine are designed to handle numbers in a serial fashion. Thus during calculations, the ten digit data words 35, Fig. 9, are processed by the arithmetic units on a digit by digit basis with machine time progressions through the units digit to the highest digit of the word. The basic cyclical timings of the machine are therefore related to digit position rather than digit value. In the arithmetic portion of the machine, the value of a digit is determined by simultaneous combinations of bit pulses on two of the seven parallel information lines.

Included with the above calculator is a ferrite core, immediate access or buffer storage device 36, Figs. 1 and 4b, and one or more random access magnetic disk data storage files or units 37, Figs. 1, 3 and 4d. The core or buffer storage device 36 is connected to selectively deliver or receive data from the drum storage 22, distributor 34 and the random access units 37. In addition, it is capable of directing stored data directly to the calculator under the control of the operation and address registers 28 and 29, respectively.

The particular type of core storage device 36 forms no part of the present invention. However, in this instance, destructive type readout is provided with readin immediately following readout within the same digit time to return the digit of data to its original position. In Fig. 7 a single bit core storage position 39 is diagrammatically shown with the appropriate digit, word, inhibit and sense lines 40, 41, 42, and 43, respectively, threaded therethrough.

In operation, assuming the core is set storing a bit, when current simultaneously flows through the digit and word lines during readout, the combined flux is sufficient to flip the magnetic setting or magnetism of the core 39. As the magnetism reverses, the flux generated is detected by the sense line 43 which directs this change to suitable utilization equipment. After readout, the current in the digit and word lines is reversed during the same digit time to again reverse the magnetism of the core and return the bit value to the core; should it be desired to prevent a readout or change in the state of the core, the inhibit line 42 is energized simultaneously with the digit and word lines 40 and 41, respectively, to produce a flux opposing the combined digit and word flux, which is sufficiently great to prevent the core from changing its state and influencing the sense line 43.

There are five 1 bit cores arranged in parallel for each digit position to represent digits in a 2-out-of-5 bit code shown more clearly in Fig. 20. In the example given, a sixty word core array is provided and represents a word group 44, as shown in Fig. 8. This group comprises sixty 10 digit words plus a sign for each which totals 660 digit positions to store the desired data. Each digit position is consecutively sampled from digit 0, word 00, through digit 10, word 59, and readout occurs over the sense lines 43, Fig. 1, parallel by bit serial by digit and word. A more complete description of the operation of a core store unit of this type appears in R. C. Greenhalgh application, Serial No. 554,583, filed December 21, 1955. Readout from the core storage is directed over the lines 45 and 46 to the core input or bit drivers 47 associated with the inhibit lines 42 for regeneration. In addition, the data may

be selectively directed over the lines 48 and 49 to the distributor 34 to drum storage 22 over the lines 48, 90 and 51, respectively, or over the lines 45 and 52 to the random access storage units 37.

5 In order to transfer data from the drum 22, the proper operation code must be presented at the operation register 29. At the proper time the data is delivered over the appropriate data lines in synchronism with the timing pulses appearing on lines 53 leading from a timing unit 54, which is operated under control of the drum 22. With data resting in the core or buffer storage 36, the drum timing 54 is disabled or disconnected from the core drivers. Whenever data is to be removed from the core storage for processing in the calculator or for storage on the drum, the drum operated timing unit 54 is utilized to drive or move the data at the desired rate. This data is directed over the lines 49 or 90, as the case may be. During the interval when the core storage is not called upon to receive or handle data, the drivers are disconnected or uncoupled from the drum timing unit. The drum timing unit 54 performs no data transfer function to the random access disk storage units 37.

As previously mentioned, the random access disk storage units 37 are provided to make available large 25 quantities of data for processing with a minimum loss in time. As shown in Figs. 1 and 3, each unit includes a plurality of disks 55 mounted on a single shaft 56 for rotation in unison. Rotation of the disks is provided by a suitable substantially constant speed drive means or motor 57. In order to selectively read or write data on one of the faces of one of the disks, a plurality of adjustable bifurcated access arms 58 are provided. Each access arm includes a pair of inwardly facing transducers or read/write magnets 59, carried or mounted on the outer 30 extremities of the bifurcated arms to embrace a single disk at a time. An electromechanical servocontrol mechanism, generally indicated at 61, is provided for each access arm 58 to radially shift the same to clear the outer periphery of the disks 55 and to vertically translate the related arm to any one of the plurality of disks. The transducers carried by the access arm are connected or coupled through suitable switching 62, Fig. 1, to either receive data from the core storage array 36 or to deliver data thereto in accordance with an operation instruction 35 to be hereinafter fully described.

40 As shown in Figs. 1 and 2a, a seek control mechanism 63 is connected through suitable switching to the distributor 34 of the calculator. Before a read or write instruction to the random access storage unit can be completed, a seek instruction word 64, Fig. 11, must be loaded into the distributor 34. After loading the distributor with the seek instruction, the operation register 29 directs the output of the distributor to the seek control circuitry 63 to initiate operation of the selected access arm 58, Figs. 1 and 3, to one of a plurality of data storing tracks 65, Fig. 5.

45 Assuming the desired access arm is properly located, with a write instruction, the operation register signals are directed over a line 66, Fig. 1, to suitable read/write control latches 67. These latches initiate operation of timing pulse generating means 68 to direct a series or group of timing pulses over a line 69 and gating switches 71 leading to the core array 36 to drive the data from the core storage for writing on the selected track. A read instruction in the operation register 29 conditions certain latches to permit the read operation to be initiated when an end of gap signal S, Fig. 14, is presented to the timing pulse generator 68, Fig. 1. Under these conditions, the data read from the track is directed over read bus lines 72 through a serial-parallel translator 73 to the bit drivers 47 in the core storage 36 for further processing.

50 Referring now to Fig. 5, coded information or data is magnetically stored on the disks 55, which include a coating of magnetic material on both sides or faces. In this particular instance, each random access file unit 37

includes fifty axially spaced disks which are mounted on the vertical shaft 56 for rotation at a substantially constant speed of 1,200 r.p.m. Because the disks are coated on both sides, each file unit contains one hundred disk faces. The reading and writing of data on the surface of these disks are performed by any of the read/write heads 59 carried by the access arms 58. Each access arm is mounted on a vertically movable carriage 74, Fig. 3, disposed adjacent the outer periphery of the disks and is capable of rapidly moving up or down to any disk. The magnetic read/write heads on each access arm 58 are moved radially across the disk faces to locate the desired track of data on the disk. In this modification, three mechanically independent access arms 58 are provided for each random access unit 37 and each arm can be independently directed to any disk track therein. This independent operation of the three access arms permits concurrent processing of three records. Fig. 5 is a schematic view of the disk face arrangement. It is to be noted each arm 58 can straddle any disk as it moves radially across seeking the track. Each arm has two read/write heads or transducers 59, the upper head is for the top sides of the disks and the lower heads read and write on the bottom sides of the disks.

Each of the one hundred disk faces in the random access file unit is further subdivided into tracks. Each disk face has one hundred tracks and each track has a capacity for storing six hundred digits of data plus sixty sign indications. Thus one random access file unit 37 contains six hundred data digits per track, one hundred tracks per disk face and one hundred disk faces per unit or a total of 6,000,000 digits. The six hundred digits per track are arranged in sixty word lengths each of ten digits and sign per word. This is shown in Figs. 8 and 9, respectively. A track therefore has a capacity of sixty words of data which may be defined as the word group labeled 44.

Access to information on any track is obtained by programming. An operation code Seek directs one of the access arms 58 to the desired disk face and track. An operation code of Read or Write is then given. The read instruction results in reading all the data serial by bit and serial by digit from the entire selected track and places the same parallel by bit in the same digit order in the immediate access or core storage 36, where it is made available for processing under normal program control.

The write instruction stores the entire sixty word content of immediate access or core storage 36 (600 digits plus signs) on the designated track as a word group 44. Either alphabetic, numerical, or special character data can be stored in the random access storage unit. Alphanumeric and special characters are stored in the same two out of five digit numerical form as described in the above-mentioned Greenhalgh application.

Checking means, not shown, for the data is provided which insures correct transmission to and from the random access storage unit 37. Information from core storage is preferably checked for validity (missing or extra bits) whenever data are either read in or read out.

After a track is written in the random storage unit 37, the track is immediately read back and checked against that in the core storage 36, thus insuring correct writing of the stored information. If for some reason an error is detected, the track is automatically rewritten and checked again until a correct check is obtained. This operation will be hereinafter discussed more fully.

It is intended that the random access data storage units 37 be permanent storage because data will remain stored indefinitely and may be read out as many times as desired. Data in storage is only changed by a write instruction, which erases a previously recorded group of sixty words, digit by digit as the new digit is written. The magnetically recorded information stored in the random access storage unit appears serial by digit, and

serial by bit, as shown in Figs. 13 and 14. The conversion from serial-serial in the storage unit 37 to serial by digit, then parallel by bit in the core storage 36 is automatically handled whenever data are transferred between the two storage media.

The schematic Fig. 5 shows the track and word arrangement for a disk face. Track 00 is the outer track, and track 99 is the inner track. The total circumferential length of a track is approximately sixty-two word lengths, where two-word lengths constitute a gap or space 75, Figs. 6, 14 and 16, followed by the sixty words of data. It is to be noted that the gap 75 and data words on a track have no physical location or fixed reference to corresponding spaces 75 and data words on any of the other tracks. This will be hereinafter more fully described.

As mentioned previously, each random access storage unit 37 contains 10,000 addressable tracks. The address 76, Fig. 11, for each track, is a six digit code that specifies, disk storage unit, disk faces, track and access arm, and is constructed as follows:

Disk storage unit numbers 0—9 (D6)
 Disk face numbers 00—99 (D5-D4)
 Track numbers 00—99 (D3-D2)
 Access arm numbers 0—2 (D1)

The remaining digits in the word 64 are not used with a random access unit address. As an example, an address of 2—04—91—1 specifies disk unit 2, disk face 04, track 91, and access arm 1.

File Unit	Disk Face	Track	Access Arm
2	04	91	1

Another example of a RAM address:

File Unit	Disk Face	Track	Access Arm
0	00	00	0

This example specifies file unit 0, disk face 00, track 00 and access arm 0.

File Unit	Disk Face	Track	Access Arm
3	99	99	2

55 The foregoing address will direct access arm 2 to the last track 99 on disk face 99 in file unit 3.

The random access complete addresses are placed in the distributor 34 by programming whenever reference to a disk unit 37 is desired. The six-position address constitutes the low order six digit positions of the distributor word. A subsequent random access operation code automatically refers to the distributor for the random access address.

Fig. 5 shows the disk face arrangement in the random access storage unit. Disk face 00 and 50 share the same disk. Disk face 01 and 51 are on the second or next disk below. It will be noted that the disk face address of the bottom of a disk is always fifty greater than the address of the top face. This aids in the head selection circuitry when reading or writing on the upper or lower surface of the disks.

Three operation codes 85, 86 and 87, respectively, are provided to the calculator programming for random access storage unit control: Seek, Read, and Write. Each 75 of these operation codes requires that the D-address 25,

Fig. 10, of the instruction word 24 be 9,000. In the case of the read and write operation codes, this D-address activates the core storage 36, Fig. 1, to function in the transfer of data from and to the disk file 37. However, the random access unit six digit code address must be in the distributor 34 when any of the above three random access instructions is initiated.

The function of an 85 operation code instruction (seek) is to cause one of the access arms 58 to move to the disk face and track specified by the random access address located in the distributor 34. The time required for the access arm to seek and find the specified disk and track varies with the distance it has to move. In this embodiment, if the address specifies a track on the same disk that the access arm is now on, the access time is about 150 to 300 milliseconds.

When the address instructs the access arm to move to another disk, the access time is greater. The maximum access time for a seek operation is approximately 800 milliseconds. To illustrate the variation in access time, a seek operation that directs the access arm 58 to move twenty-five disks takes about 500 milliseconds. When an access arm moves the maximum distance of forty-nine disks on a seek operation, the access time can be up to 800 milliseconds.

Because data are recorded on both sides of a disk, track 00 of disk face 00 is directly above track 00 of disk face 50. Therefore, if the access arm 58 is located on track 00 of disk face 00, the minimum access time for a seek operation would be to track 00 on disk face 50. This access time is about thirty milliseconds. This access time overlaps the calculator programming. The calculator is interlocked only for two word times (192 microseconds), which is the time it takes to transfer the random access address from the distributor 34 to a random access address selection unit 77, Fig. 2a.

The D address 25, Fig. 10, of the seek instruction is 9,000, and the six digit random access address 76, Fig. 11, must be in the distributor 34, Fig. 1, for the two word times during which the seek instruction is initiated.

A write random access operation code 87 presumes that a previous seek instruction 85 has positioned the desired access arm 58 at the correct track. If the seek operation has not been completed, the write instruction automatically waits until the read/write head 59 is in position on the designated track.

The function of the write operation code 87 is to cause the entire contents of the core storage 36 to be recorded on the selected track. The D address 25 of the write random access instruction is 9,000, and the 6 digit random access address 76 must be in the distributor 34 for the two word times during which the seek instruction is initiated.

The write random access disk unit operation begins by checking the address in the distributor 34 to insure that the correct track has been selected by the prior seek instruction. As soon as the address is checked and confirmed, the write operation begins immediately. Any previous data on the track are erased as new data are written. Approximately a four-word length erase gap 78, Fig. 15, is provided followed by writing the sixty words of data from the buffer core storage 36, Fig. 1. After writing provides sixty words provides the gap 75, Fig. 16, is provided which is approximately two words in length, between the first and last bit recorded to designate the starting point of the data on the track for future random access read operations. Each time data are written on a track, the previous data are erased and a new two-word gap 75 and data recording are made. This writing of data takes one revolution of the disk 55.

As each digit is read out from the core storage 36, it is checked for validity, by means not shown. However, to insure further that correct data were written on the track, an automatic write-check cycle is taken. The write-check cycle causes both the newly recorded track and core stor-

age 36 to read out their data serial by digit to a write character comparing unit 79, Figs. 1 and 4c. This comparing unit checks each digit written on the track against the corresponding digit from the core storage for identical code structure and for validity. The write-check cycle also takes one revolution of the disk.

The write random access instruction requires approximately 120 milliseconds. This is composed of two disk revolutions of fifty milliseconds each and twenty milliseconds of setup time. The core storage unit 36 is interlocked for the complete 120 milliseconds. Therefore, the calculator can be programmed to execute other instructions that do not refer to the core storage unit, while the write random access instruction is being executed.

A read random access operation code 86 presumes that a previous seek instruction has positioned the selected read/write head 59 at the correct track. If the seek operation has not been completed, the read instruction automatically waits until the read/write head is in position on the designated track.

The function of the read random access operation code 86 is to read an entire track of 600 digits of data and place it in the buffer storage unit 36. The D address 25 of the read instruction is also 9,000, and the six digit random access address 76 must be in the distributor 34 for the two word times during which the instruction is being initiated, the same as during a write instruction.

The read random access operation begins by checking the address in the distributor 34 to insure that the correct track has been selected by the prior seek instruction. As soon as the address is checked and confirmed, the read operation begins searching for the two-word length space 75 on the track. This space indicates the starting point of data previously written on the track. Because the disks 55 are continuously rotating, the space could be immediately available or a maximum of a complete disk revolution away from the associated read head 59. When the track space is recognized, the entire track of 600 digits of data is read and transferred to the core buffer storage unit 36 in the time it takes for one revolution of the disk. As each digit is read from the track, it is checked for validity, by means not shown. If a validity error is recognized, the track is again read into the core storage and a validity check made on the transmitted data. If the validity error persists, the read operation is repeated until a correct transmission of all 600 digits is made to core storage or until manual intervention by the operator halts the operation.

The total time for a read random access instruction varies from approximately seventy milliseconds to 120 milliseconds. This maximum limit assumes that the transmitted data satisfactorily pass the validity check. An average time for a read operation is 95 to 100 milliseconds. The read random access storage timing is comprised of twenty milliseconds setup time; fifty milliseconds to read the complete track; and a variable time from zero to fifty milliseconds, which is dictated by the proximity of the track space 75 to the read head 59 at the beginning of the read operation. Immediate access core storage 36 is interlocked for the entire read random access operation. The calculator is interlocked for only two word times (192 microseconds) and is free to execute other instructions that do not refer to the core storage unit.

Referring now to Fig. 6, the top plan view of disk face 00 is shown along with a number of the one hundred circular tracks or data storing paths. It is to be understood, of course, that these tracks of stored data are generated by rotation of the disk 55 past the read/write head or transducer 59 after the latter has been radially positioned at one of the one hundred possible track positions by its related access arm 58. Since each disk face with the tracks thereon is identical, the description will be confined to one track and one disk face with the understanding the same description would be applicable to all tracks and disk faces.

As previously mentioned, each circular track is approximately sixty-two words in length and the data defining a word group of sixty words, word 00 through word 59, occupies sixty words of this track to leave the approximate two-word gap or space 75 between the first and last recorded bits S and 79, respectively, Fig. 14. Since the circumference of each track varies in length from track to track, moving in a radial direction, it can be seen that the circumferential length of each digit position and word will vary accordingly. Thus the distance between each bit recording will not be uniform. However, this will not affect the reading and recording operation because the time required for the disk revolution is the same per revolution. Since the read and write mechanisms are not sensitive to the length of space between bits, the particular length of a bit position has no bearing on the read and write operations. In this embodiment, the nonreturn-to-zero, NRZ, type of recording is utilized as diagrammatically shown in Fig. 14. A more complete description of the means for accomplishing the NRZ flux pattern appears in B. E. Phelps Patent 2,774,646, issued December 18, 1956.

Fig. 14 is intended to represent the flux pattern, indicated as a continuous line 81, on a track for an arbitrary word of data, along with the gap or space 75 between the beginning and end of a word group 44. When the flux line 81 is down, it is assumed the magnetism along that portion of the track is negative or in one direction, and when the flux line is up, the magnetism along that portion of the track is positive or in the opposite direction. It is only at the point of change in flux, indicated by the vertical lines and defined as a bit position, that the sensing equipment responds to generate an output signal which is directed to suitable apparatus for decoding or recording for further use. Likewise, during writing, each delivered bit causes reversal of the current in the read/write head 59 to change the flux pattern on the surface, as indicated.

The digit positions D0-D10 follow serially along the track and each digit position is further subdivided into serial weighted bit positions, as shown in Fig. 13, to provide S, 6, 3, 2, 1, and 0 serial bit locations for each digit. Thus to record a decimal 6 serial by bit, a change in flux must occur at the 6 and 0 bit times or locations. While Fig. 14 for digit position D1 shows a vertical drop at 6 bit time and a rise at 0 bit time, this could be reversed because the sensing means only detects the change in state and not the direction or the duration.

In Fig. 14 it is assumed the group of words have been written on the track and the S bit, to be hereinafter described, at the beginning or space bit position of the first digit has been generated to signify or indicate the end of gap or space, and this is followed by the word group recorded serial by bit, digit and word in the manner indicated.

By way of example only, an arbitrary numeric word of data 76105983512 is indicated in word 00. With the beginning of word 00, digit D0, the flux pattern changes to the positive or up position at the S or space bit position and this state continues until the 6 bit position is reached. At this point, the flux pattern is again reversed to its negative or down value and so remains until the 1 bit position is reached. At this time the flux again reverses to the positive value and the 2-out-of-5 reading for this particular digit position D0 has been completed and a decimal 7 has been indicated. The same pattern occurs at digit 1, D1, which is storing a decimal 6; however, the flux reversals occur at the 6 and 0 bit positions instead of the 6 and 1 bit positions. The remaining numeric values follow in the same manner.

It will be noted that each digit position includes a change in flux at two and only two bit positions within the digit to always return the flux pattern to the same side as it crosses from one digit to the next. Also that the S or space bit positions of the digits following digit 0, word 00, are left blank. As word 00 is completed, digit

D0 of word 01 immediately follows and this occurs serial by digit from word to word.

At the space bit position of digit D10, word 59, a second S bit signal is provided prior to the two bits of the last digit. This second S bit is necessary to provide an even number of bits or flux changes along the track or path so that the flux pattern returns to its original space indicating position in a uniform manner. With the group of words recorded on the track, the data may be permanently stored and read in a nondestructive manner whenever desired.

Should it be desired to modify the data or any part thereof in the track, this data is read and directed to the core storage 36 for processing or modification in the calculator. When the data are properly rearranged for recording, the random access write operation code 87 initiates a recording or write operation. With the selected read/write head positioned at the track, an erase operation is immediately initiated at random along the circumference of the track without regard to the physical location or positioning of the previously recorded word group.

As shown in Fig. 15, for example, the previous space between the recorded word group is arbitrarily located at the left-hand side of the sheet and for the purpose of this description, it is assumed the write signal was received when the digit position D8 of the previously recorded word 00 was under the read/write head 59. As shown, all previously recorded data following digit D8 is erased or removed by continuously driving current through the transducer or read/write head 59 in one direction to drive the flux pattern down or negative. This continuous erase operation extends for approximately four word times and is controlled by a suitable clock driven gap ring. At the end of the four word erase, an end of gap or S bit signal is automatically generated and recorded on the track by changing the direction of the flux at the read/write head 59 at the space bit timing or beginning of a digit. From this point on the sixty words of data are recorded in the manner previously described.

40 The recording of the new data erases any of the previous data at the particular location before new recording takes place.

As shown in Fig. 16, the fifty-ninth and sixtieth words will be recorded in the forward or initial portion 45 of the erased section of the track. While the modification discloses a two-word overlap into the erased section of the track, it is to be understood that this overlap can vary in either direction. In fact, it would only be necessary to overlap by one digit or bit position. However, due to the separate driving means which provide variable conditions with respect to disk rotation and clocking pulses, the additional overlap provides a margin of safety to insure the removal of any of the previously recorded data.

55 Fig. 17a diagrammatically indicates the beginning of a recording operation starting with a four word erase; Fig. 17b, the end of the four word erase operation; Fig. 17c shows the recording operation in progress; and Fig. 17d, the end of a recording operation with the recording overlapping in a portion of the erased section.

After the recording operation is completed, the newly recorded gap 75 must always be sensed before a reading operation can be initiated.

Should it be desired to modify the data on any track, 65 the previously-described procedure is followed. Thus it can be seen that each write operation may be initiated at random along the circumference of the track and this random writing occurs with each recording on the same track. Likewise, the writing may occur at random 70 along the circumference of any of the tracks without regard to the circumferential location of the starting positions of any of the word groups on any of the other tracks. This same condition prevails from disk face to disk face and disk storage unit to unit. A recording operation of this type is effective to increase the over-all

operating speed of a data processing machine on an average of twenty-five milliseconds for each write operation.

Circuit description

Referring now to Figs. 2a and 2b, 3 and 4a to 4d for a more complete description of the more essential circuitry required for operation of the random access storage unit 37, only the distributor 34, Fig. 2a, of the calculator 21 is shown. The disk storage unit address 76 Fig. 11 may be taken from an address on the drum 22, Fig. 1, and loaded into the distributor under control of an instruction supplied by the operation and address registers 28 and 29, respectively. It is to be noted the random access address 76 occupies six digit positions D1 to D6, inclusive, of the word. The remaining digit positions in the word are ignored. However, zeros are normally inserted at D0 and D7 through D10 to satisfy the validity check for the calculator system.

After the distributor 34 is loaded with the random access address, the next instruction appearing in the operation register 29 may be a seek instruction code 85. A seek instruction operates over a line 66 and enables switching to permit operation of the seek controls 63. At the proper time a distributor digit ring 88 is operated to drive the instruction for readout. As readout occurs from the distributor 34, parallel by bit and serial by digit, over seven biquinary lines 89, only one of which is shown, the related latches 91 are operated to condition lines 92 (see Fig. 2a) leading to a translator 93. These seven input lines are weighted in the order shown in Fig. 19 and the output from the translator 93 provides a 2-out-of-5 bit code over parallel output lines 94 weighted as shown in Fig. 20.

At D1 time a digit ring D1 line 95, Fig. 2a, operates a 2-out-of-5 to a 1-out-of-3 translator 96 which switches a decimal 0, 1, or 2 representation appearing on the output lines 94 to condition, over a line 97, one control grid each of ten thyatrons arranged in one row of a three-row, thirty access relay gas tube or thyatron matrix 98. Translating a value at digit D1 time indicates which access arm 58 (0, 1, or 2) is to be actuated in a yet-to-be selected disk storage unit 37. Thus a translated 0 indicates access arm No. 0 of one of the units, a translated 1, the No. 1 arm of a unit, and a 2, the No. 2 arm of a unit. In this example, it will be assumed that a decimal 0 appears in digit D1 position of the distributor 34, therefore, the grids of the ten thyatrons in the row associated with the 0 output line 97 of the 1-out-of-3 translator 96 is conditioned.

At digit times D2, D3, D4, and D5, the output from like data storing positions in the distributor feed through the translator 93 to condition various control grids arranged in five columns in a twenty-disk and track gas tube or thyatron matrix 99. The other grids in this matrix are consecutively conditioned row by row at digit times D2, D3, D4, and D5 by the output of the related digit rings. Wherever coincidence occurs between the conditioned row and columns corresponding to the readout from the distributor for that digit position, two of the thyatrons in the row will fire and remain conducting. Thus at digit 5 time, eight of the twenty thyatrons will be conducting over separate lines 101 in parallel to a plurality of address relays 102, Fig. 2b, forming part of the seek servocontrol 61, Figs. 1 and 3. There is one set of address relays 102, Fig. 2b, parallel connected to the twenty thyatron matrix 99, Fig. 2a, in an identical manner for each access arm 58 in each disk storage unit 37.

At digit 6 time, the desired disk unit selection data is delivered over the lines 94 to a 2-out-of-5 to 1-out-of-10 translator 103 which is simultaneously gated with the digit D6 ring output. As the translated value leaves this latter translator over one of the lines 104, it conditions one of ten columns in the access relay thyatron

matrix 98. In this manner coincidence occurs at one of the thyatrons in one of the previously conditioned rows. In this example, it will be assumed that the upper left-hand corner thyatron 105 in the thirty thyatron matrix 98 fires and conducts over the line 106. During this interval the remaining twenty-nine lines 108 leading to individual access arm relays R109, Fig. 2b, are down or in their not-conducting state. The line 106 extending from the thyatron 105, Fig. 2a, is connected to the access arm relay R107, Fig. 2b, which under the above conditions is picked to transfer a plurality of contacts 111, some of which are connected to the output from the twenty-disk and track thyatron matrix 99, Fig. 2a, over the lines 101.

As the above relay R107, Fig. 2b, transfers, the output from the eight fired thyatrons conducts over their respective lines 101 and related contacts 111 to associated pick and hold relays in the address relay array 102. The affected relays are energized and transfer a group of contacts, not shown, in relay tree networks 112 and 113, respectively, Fig. 3, in any suitable manner.

Each array of address relays 102 is arranged in four columns 114, 115, 116 and 117, respectively, Fig. 2b, of five relays, each of which are weighted to provide the two-out-of-five 6, 3, 2, 1, 0 code. Two of the groups, columns 116 and 117, are defined as disk address relays and the remaining two, columns 114 and 115, as track address relays. As shown, columns 114 and 115 correspond to the units and tens position in the D2 and D3 positions of the distributor 34, Fig. 2a. Likewise, columns 116 and 117, Fig. 2b, correspond to the units and tens position in the D4 and D5 positions in the distributor. Thus every address value appearing in the D2-D5 positions in the distributor will eventually appear in the 2-out-of-5 code in one of the address relays arrays 102 to provide for the units and tens values for disk and track selection.

As two out of five of each of the columns of relays pick, a group of diagrammatically indicated 2-out-of-5 check contacts 118 in each column are transferred which feed serially through each array in any suitable manner and over a line 119 to a 2-out-of-5 check disk and track selection relay R121, Fig. 2a. If the proper pairs of address relays have been picked, relay R121 is energized to close its related contact R121a which in turn is in series with a 1-out-of-30 check access arm contact R122a associated with a check access arm relay R122. Associated with each access arm relay R122 are a plurality of series parallel connected checking contacts 123, Fig. 2b. If only one out of thirty of the access arm contacts 123 has been energized, access arm check line 124 conducts and contact R122a, Fig. 2a, is transferred to complete a circuit over a line 130 leading to a thyatron plate circuit relay R125. Transfer of the associated contact R125a is operative to open the plate circuits 126 leading to all of the thyatrons in both matrices 98 and 99 to extinguish any of the fired thyatrons. Opening of the plate circuits will release access arm relay R107, Fig. 2b, to return the related contacts to their normal opened condition. However, the two picked relays in each of the four columns in that particular address relay array 102 will remain transferred. The matrices are now in condition to process the next random access address to set up other access arms associated with the same or other disk storage units. In this manner all three arms may be consecutively addressed to different tracks and the access arms can be all simultaneously moving to their respective tracks.

As the address relays 102 are energized, the disk relays in the columns 115 and 116 selectively transfer a group of contacts in the relay tree 112, Fig. 3, to complete one of a plurality of single circuits 127 from a ground to a floating power supply included as part of an electromechanical servomechanism 123. This includes a tapped variable resistor 129 and a related wiper arm 131 carried by the vertically operated access arm carriage 74.

In addition, the relays in the track address columns 114 and 115 operate through the double tree 113 in any standard manner to provide a null point on the related resistor 132, which in turn is associated with a wiper arm 133 carried by the related access arm 58.

The particular selection of the address relays determines the null points at the related resistors which in turn determine the direction of movement of the related access arm 58. For example, if the access arm is to move from a track on disk 1 to a track at some other location on another disk, the disk and track relays are operative to establish the various potentials which determine the direction of access arm movement. In this case a constant speed motor 134 operates a differential 135 to drive a reel 136 in opposite directions under the control of a pair of direction control clutches 137. Selective operation of the clutches 137 is determined the reel 136 is such as to retract the arm 58 from the associated disk by reeling the drive cord 140 in the proper direction. As this occurs, an abutment 139 actuates a contact 141 to energize a relay R142 which in turn operates through contact R142a to permit the vertical or disk relay tree 112 to now control vertical movement of the access arm 58.

As the access arm 58 approaches the proper disk, the wiper contact 131 reaches the null point which in turn operates through a null amplifier and a coil 143 to energize a disk detent 144 to prevent further vertical movement of the access arm. Operation of the detent 144 insures that further rotation of the motor driven reel 136 will move the access arm radially in the direction of the desired track. As the access arm reaches the desired track, the wiper 133 engages the related null point of the double tree 132 which is effective to energize a coil 145 to drive a track detent 146 to home position. Thus the read/write heads 59 on that particular access arm are positioned in accordance with the instruction initially placed in the distributor.

The above briefly describes a seek operation and merely generally discloses an electromechanical servomechanism to move a read/write head or transducer 59 from one location to another. A more complete description of the exact operation of a suitable device of this type is more fully described in the above-mentioned Stevens et al. application. It is to be understood, however, any suitable servomechanism may be utilized to shift the access arm 58 to the desired location.

Each unit may include any number of access arms 58 identically operated; however, in this embodiment the optimum appears to be three access arms per disk storage unit.

When the access arm selection relay R107, Fig. 2b, transfers, a related contact R107a closes, and certain of the relay points in the column 117, representing the tens position of the disk address relays are transferred. The closure of the various contacts determines whether the upper or lower read/write head or transducer 59 of that particular access arm 58 is to be utilized. For example, if the tens position of the disk address includes a 0, 1, 2, 3, or 4, contacts R0a and/or R1a close or R3a remains normal and the upper read/write head relay R147 on the selected access arm is energized to close related contacts R147a and R147b, Fig. 4d. Closing of these contacts permits the upper transducer to read or write on the upper faces of any of the fifty disks, 00 to 49. If a 5, 6, 7, 8, or 9 appears in the tens position, transferred contacts R2a and R3a, Fig. 2b, in series or R6a alone energizes lower head relay R148 to close related contacts R148a and R148b, Fig. 4d, to condition the lower read/write head of the selected access arm for all lower disk faces 51 to 99 in the same manner.

When either the upper or lower head is selected, one of the contacts R147c or R148c, Fig. 2b, transfer to energize a bus line relay R149 which closes related contacts R149a and R149b to provide a disk storage unit

selection, see also Fig. 4d. With an arrangement of this type, a plurality of disk storage units 37 may be connected to the same input and output lines 52 and 72, respectively. Each group of address relays includes 5 similarly operated upper, lower and bus line relays which operate in the same manner. Since the particular relay design forms no part of the invention other than to control which unit and head is made operative, a further description is not deemed necessary.

10 Referring now to Figs. 4a to 4d, there is diagrammatically shown a control arrangement for transferring data from the temporary buffer or core storage device 36, Fig. 4b, to a selected track in one of the disk storage units 37, Fig. 4d. Assuming first that data is to be placed in the core storage from an external source, such as the data processing machine or drum storage 22, Fig. 1, the calculator ring control line and calculator digit ring driver lines 151 and 53, respectively, Fig. 4a, are raised to condition a diode switch 153 which conducts through a diode mix 154 over a line 155 to digit 0 of the closed digit ring 156. At the same time word ring 60, Fig. 2b is conditioned over a line 157. Consecutively received digit pulses, supplied from the drum driven timer 54, Fig. 1, over the digit drive ring line 53, Fig. 2a, advance the digit ring 156 digit by digit. Each complete cycle or revolution of the closed digit ring 156 provides a signal over a line 158 leading to a diode switch 159 which is conditioned by the calculator ring control line 151 to drive a pulse through a diode mix 160 and over a line 161 to advance the word ring 162 one word, Fig. 4b.

25 During this interval, the words of data to be stored are delivered from the drum 22, Fig. 1, over the lines 163 and 164, Fig. 4a, and is presented parallel by bit 35 and serial by digit to the bit drivers 47, Fig. 4b, associated with the inhibit lines 42 for storage in the conditioned digit position and word in core storage 36. During this interval, previously recorded data is destroyed by blocking the output from the bit register sense latches 165.

40 The operation of the digit and word rings along with function of the readin and readout at the inhibit and sense lines 42 and 43, respectively, is more fully described in the previously-mentioned Greenhalgh application. The only explanation which appears necessary in this application is that normally readout and readin occur at the same digit time by timed pulses supplied to the digit, and bit drivers 50, 60 and 47, respectively, over the readout and readin lines 70 and 80, respectively, as indicated by the pulse superimposed on these lines. When 45 the entire sixty words are placed in the core storage device 36, the calculator ring control and digit ring driver lines 151 and 53, respectively, are disconnected or dropped, and it is now possible to write this data on a selected track.

55 In order to connect the core storage 36 with the disk storage 37, the disk storage ring control line 166, Fig. 4a, is raised to condition a pair of diode switches 167 and 168, respectively. The line 166 is under the control of the operation register 29. As previously mentioned, the 60 desired track is selected by placing the address in the distributor 34, Figs. 1 and 2a, which in turn operates through the address relays, Fig. 2b, and servomechanism, Fig. 3, to position the selected access arm 58 at the desired disk and track and at the same time operate the 65 relays R147, R148 and R149, Fig. 2b, and related contacts, Fig. 4d, to condition the upper or lower transducer 59 on the selected arm for operation.

Assuming the above track selection operation has 70 taken place with the access arm resting at track 50 on disk face 01, and has been checked by comparing the addresses in the relays 102, Fig. 2b, and distributor 34 and found correct, a write operation code 87 is placed in the operation register 29, Figs. 1 and 4c. This code 75 provides an output from a diode switch analyzing cir-

cuit 169 to turn On a write mode latch 171 which latch acts to turn On a write gap latch 172.

As the write gap latch turns On, lines 173 and 174 are raised to bias a write amplifier 175, Fig. 4d, in one direction to provide current over output lines 176 and 177 through the selected read/write head 59 whose related contacts R147a and R147b have been closed. This produces a flux pattern which is uniform in one direction and acts through the erase coil 178 to remove all previously recorded data, as shown in Figs. 14 to 16.

At the same time the line 173, Fig. 4c, operates a write gate latch 179 having an output line 181 coupled to an oscillator unit A in the pulse generating unit 68. The output from the write gate 179 causes oscillator A to continuously operate and provide an oscillating output to a clock pulse mechanism 182. This clock mechanism in turn provides consecutive timed pulses, as shown in Fig. 18, over the line 69 to a closed bit ring 184, Fig. 4a, having six bit positions; that is, S, 6, 3, 2, 1, and 0. Each clock pulse consecutively advances the bit ring 184 from bit position to bit position in a serial manner in the above order. With the disk storage ring control line 166 positive, each complete revolution or cycle of the bit ring 184 conducts over a line 185 to the diode switch 168 which provides an output over the line 155 to the digit ring 156 to advance the same one digit position. Thus for each eleven complete cycles of the bit ring 184, the digit ring 156 completes one revolution or cycle.

In the above and following description, it is assumed the bit, digit, and word rings 184, 156, and 162, respectively, Fig. 4b, normally rest at their S bit, D0 and W00 positions, respectively. Therefore, these positions will be the first ones acted upon during both reading and writing operations.

Due to the fact the write amplifier 175, Fig. 4d, is biased in one direction and is performing an erase operation on the selected track, it is not desired to read or drive any data from the core storage device 36, Fig. 4b, until the proper erase phase has been completed. Thus the diode switch 167, Fig. 4a, connected to the digit ring output line 158 is held down by a negative output applied over a line 186 associated with a write end gap latch 187. As the digit ring 156 completes its revolution, the output on the line 158 cannot pass through the diode switch 167; however, a gap ring 188 is advanced one position for each complete cycle of the digit ring. At the end of a predetermined number of digit cycles, four in the example given, a positive output is driven over a line 189 to operate the end of gap latch 187. Operation of this latch conducts over lines 191 and 186 to condition the diode switch 167 leading to the word ring and word 00, Fig. 4b, for readout.

As the end of gap latch 187, Fig. 4a, goes on to raise word 00, the digit ring 156 is resting at D0. These positive values are conducted over word 00 and digit 0 lines 192 and 193, respectively, to a diode switch 194, Fig. 4c. This switch also includes input lines 195 and 196 which respond to the clock pulse mechanism 182 and the S bit position in the bit ring 184, Fig. 4a. Positive coincidence of all four values generates a pulse at the switch 194, Fig. 4c, before the first bit position of the digit is sampled. This combination of positive values extends through a diode mix 197 and over the line 52 having the closed contact R149a, Fig. 4d, of the unit relay R149 therein to operate a binary latch 199.

At the same time the end write gap latch 187, Fig. 4a, goes On, a positive value is conducted from the output over lines 191 and 201 to turn Off the write gap latch 172, Fig. 4c, which drops line 174 to remove the bias from the write amplifier 175, Fig. 4d. However, the write gate 179, Fig. 4c, remains up to continue operation of the oscillator A and the clock 182. Dropping the write gap latch 172 turns on a write record latch

202. Operation of the write record latch raises write record line 203 and a diode switch 204 disposed at the output side of a parallel-serial translator 205 and at the same time conditions the switches 206, Fig. 4d, at the output of the binary latch 199. A binary latch operates somewhat similar to a bistable trigger; that is, each pulse flips the latch from one side to the other to provide alternate voltage levels at its output to selectively drive the write amplifier 175 from one side or the other. This causes reversal of the current flowing through the lines 176 and 177 when connected to the selected read/write head or transducer 59 to provide opposite flux patterns on the track upon the arrival of each bit at the input side of the binary latch 199.

With the arrival of the generated S bit, which has no relationship with the circumferential position of any particular point on the track, a change in flux is generated on the track as described when discussing Fig. 14. From this point on, the selected disk storage unit 37 is ready to receive the data.

In order to translate the parallel by bit, serial by digit data in the core storage 36 to serial by bit and digit, an output line is provided from each of the 6, 3, 2, 1, and 0 bit stages in the bit ring 184, Fig. 4a, to the parallel-serial translator 205, Fig. 4c. These bit lines set up a series of latches or the like in a predetermined manner and as readout occurs from the first digit position in the core 36, Fig. 4b, to the bit register sense latches 165, these values are conducted over the 2-out-of-5 bit lines 45 in parallel to the parallel-serial translator 205, Fig. 4c. With each cycle of the bit ring 184, various combinations of the input lines 45 are sampled and the bit values leave the translator 205, within a digit time, serial by bit over the line 209 in the timed relationship shown in Fig.

35 13. The bit values are switched with clock pulses supplied over the line 195 at the diode switch 204 to drive over the line 52, Fig. 4d, and alternately operate the binary latch 199 to provide the alternate positive outputs leading to the input of the write amplifier 175. Alternate driving of the amplifier changes the current flow over the lines 176 and 177 to reverse the flux pattern at the transducers 59 as previously described and shown in Fig. 14.

The digit value read from core storage is returned 45 within the same digit time. This is accomplished by presenting the same bit values delivered for translation over the connecting lines 46 leading to the core input and bit drivers 47. These values appear on the inhibit lines 42, Fig. 4b, for regeneration of the previously read 50 information in the same digit position.

Recording of the values at each digit position occurs in an identical manner, digit by digit and by word until the beginning of word 59, digit 10, as shown in Fig. 14. As digit 10 of word 59 appears, positive values are directed over the respective digit and word lines 211 and 212 to a diode switch 213, Fig. 4c, and an S bit is generated by gating the S bit in the bit ring 184 over the line 196 with a clock pulse over the line 195. This bit signal operates the binary latch 199 at the space bit position and signifies that an end of record is approaching. Recording of the S bit in the track is primarily utilized to provide an even bit count along the track to return the flux pattern to the original condition.

As bit 0, digit 10, word 59 time arrives, an output over 65 the 0 bit line 214, Fig. 4a, is directed to an end of ring diode switch 215, which has been conditioned by the digit 10 and word 59 lines 211 and 212, respectively. This produces an end of ring signal extending over an end of ring line 216 and turns Off the write gate 179, Fig. 4c, to stop the oscillator A and clock 182. At the same time the write record latch 202 is turned Off to drop the write record line 203, which drops the diode switch 204 at the output side of the parallel-serial translator 205 and the output from the binary latch 199, Fig. 4d. This completes the writing operation and includes 70 75

the sixty words in the core storage device 36 which have been regenerated as described.

In order to insure that the data in the core storage 36, Fig. 4b, corresponds to that written on the track by the read/write heads 59, Fig. 4d, a write check operation is automatically initiated. As the write record latch 202, Fig. 4c, turns Off, a write check latch 217 is energized to raise its output line 218. During this interval, it is necessary to defer or prevent read out of the core storage 36, until such time as the end of gap record or generated S bit on the selected track appears under the associated transducer 59. Detection of the first bit causes a current flow over the lines 176 and 177, Fig. 4d, which extends to a read amplifier 219. The output from the amplifier is impressed over the read bus lines 72 to permit synchronization of the system.

As the S bit passes over the read bus line 72, which was conditioned by the write record line 218, to the diode switch 220, Fig. 4c, an output is directed over a line 221 and operates a binary latch 222, Fig. 4c, to start the oscillator A which in turn operates the clock 182 in the described manner to provide continuous clock pulses over the lines 69 and 195. At the same time this first pulse on the line 221 turns On a read latch 223, Fig. 4a, to cause a read diode switch 224 to provide an output. This diode switch had previously been conditioned by the S bit line 196 extending from the bit ring 184 and the write check latch line 218. The output from this switch extends over a conductor 225 to a latch 226 to turn the same On, which in turn drives over a conductor 227 through a diode mix and the conductor 186 to condition the diode switch 167 associated with the output of digit ring 156 over line 158. Conditioning of this latter switch bypasses the gap ring 188, which was utilized to provide the gap prior to the actual write operation.

With clock operation initiated by the S bit appearing on the read bus line 72, the bit ring drive is started and the clock pulses are directed to a read diode switch 228, Fig. 4c, which is also connected to the bus line 72. From this point the serial arrival of the bits on the line 72 are switched with the clock pulses and are directed over a line 229 to suitable switching 230, Fig. 4a, leading to the serial-parallel translator 73. This translator comprises suitable groups of latches or the like which serially accept the coded bit values delivered at each bit interval and store the same to provide a parallel positive pulse readout over bit lines 232 leading to individual inverters 231 whose individual outputs are connected to the comparing unit 79, Fig. 14c. The inverters 231 are included to provide positive values on their related bit lines 207 in the absence of a positive pulse on the bit lines 232.

During the reading of the first digit from the track, the first digit position, bearing the same data, is read from core memory 36 over the line 45 and presented to the comparing mechanism or unit 79. This comparing mechanism is shown diagrammatically and may include a plurality of diode switches or the like 208, only one of which is shown, for each pair of bit lines connected to parallel inputs so that similar bit lines are simultaneously sampled to determine if they are in like conditions for each digit position. If each bit line for that particular digit value agrees, the inverters 231 provide selective positive and negative values on the related output lines 207, which are opposite to the values delivered over the line 45 to the diode switches 208. Therefore, an output line 210 from each switch 243 remains down. This indicates that a true or correct writing operation had taken place. If in error, the bit values delivered to the related inverters 231 drive the related output lines negative while the remaining lines stay positive. These positive values switch with certain of the positive values arriving over the lines 45 at one of the diode switches 208 and a signal is provided over the line 210 to operate a bit comparing error latch 246. As each digit position is

serially presented for comparison, the data read from that particular digit in core memory 36 is returned during the regeneration interval for storage and the information in the serial-parallel translator is destroyed by a 5 reset operation or pulse supplied over a reset line 183.

At the end of a complete check, that is, digit 10, word 59, an end of ring signal is presented from the diode switch 215, Fig. 4a, over the line 216 to turn the read latch 223 Off and to the write check latch 217, Fig. 4c, 10 to turn the same Off. The writing and checking operation have now been completed, and the data is available for any future use.

Should an error be indicated between the recorded data on the track and similar digit positions in the core storage 15 36, a signal from the comparing unit 79, Fig. 4c, is delivered from the bit compare latches 246 over a no- 20 compare line 234 to again turn On the write mode latch 171. This operation immediately initiates a second complete writing operation identical to that previously described. Under these conditions, random writing is initiated, and all of the previous data is re-recorded; however, the circumferential location may vary.

A read operation is somewhat similar to a write check operation in that the write amplifiers 175, Fig. 4d, are 25 prevented from effecting any change in flux pattern. With a read operation code 86 in the operation register 29, Fig. 4c, a read mode is initiated by operation of one or more read latches 236, which provide an output over a line 237 to a diode switch 238. The output from this 30 switch extends over the line 221 to operate the binary latch 222 and the latch 223, Fig. 4a, when the S bit arrives to initiate the reading of data from the track. During a read operation, all data delivered to the read amplifiers 219, Fig. 4d, appear on the read bus line 72 and 35 is presented to the serial-parallel translator 73, Fig. 4a, serial by bit, as mentioned for write check. The only exceptions between the write check and read operation is that no comparison is made in the comparing unit 79 at this time and that the serial-parallel translator 73 40 provides an output which is presented to the bit drivers 47, Fig. 4b, for storage in core memory parallel by digit, after the bits in each digit are accumulated in the translator 73. The line 237 extending from the read latches may be directed to the serial-parallel translator 73 to 45 effect the parallel readout to the bit drivers 47.

Referring now to Fig. 18 for a brief description of the timing utilized during a read and write check, there is shown the timing relation of the various bit signals appearing in several of the digit positions and the beginning of a record. The first pulse 240 appearing over the bus line 72 is located in the space bit position of the first digit. The leading edge of the first or S bit is effective to operate the A side of the binary latch 222, Fig. 4c, as shown at 50 241, which provides an output to start the oscillator A whose output in turn directs a wave shape 242, Fig. 18, to the clock 182. Operation of the clock generates shaped pulses 243 for delivery to the system and is utilized in the switching for the delivered bit pulses and to drive the bit, digit, and word rings in synchronism therewith. The leading edge of the next bit 244 again 55 operates the binary latch to raise the B side, not shown, and drop the A which cuts off the oscillator A. However, before the clock 182 stops, the B side of the binary latch initiates operation of the oscillator B to provide a wave shape 245. This output is directed to the clock to 60 keep the same running at the proper rate. The leading edge of each bit thus acts to alternately drive the clock for the A and B oscillators. In this manner, the clock remains in phase with the delivered bits. Since the particular type of timing means forms no part of the invention, the above description is all that is deemed necessary. However, an oscillator of the type described for use in this system is shown in L. Seader application, Serial 70 No. 537,260, filed September 28, 1955, and assigned to the assignee of the present invention.

It is to be understood that various additional timing pulses, switching, and the like not shown would be required to transfer the data to and from the core storage. However, these additional elements, if shown, would merely tend to complicate both the description and drawings without aiding in the understanding of the invention. Therefore, for the sake of simplification, all elements not bearing directly to the data transfer system have been eliminated.

From the above it can be seen that a random access, magnetic disk storage system has been provided, wherein the recording of data may be accomplished on a circular track in a random manner along the circumference without regard to any particular home position and that this random recording will occur each time data is recorded on the track and will vary from track to track, disk to disk, or unit to unit. Also any read or read-check cycle is solely dependent upon the sensing of an end of gap bit which initiates operation of clock pulses by means of the binary latch and associated oscillators. With reading and recording taking place at any circumferential point along the circular track, the requirement of precise timing with some position on the disk has been eliminated. In this manner the various units may be operating at various speeds within predetermined limits, without effecting the transfer of data between the storage and random access unit. With increased recording speeds applied to a data processing system requiring a large number of data transfers to and from a large random access storage unit, a considerable saving in processing time is realized.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a device for storing data in digit positions recorded thereat to provide coded character representations, the combination of a storage medium, a transducer associated with said storage medium, means for relatively moving said storage medium and transducer to describe a circular data storing track on said storage medium, means for selectively shifting said storage medium and transducer to provide a plurality of circular data storing tracks, a buffer storage means for the data to be recorded, means for initiating an erasing operation at random along the selected track, means for delivering the data from said buffer storage means for recording on the track with at least the last recorded digit overlapping a section of the previously erased portion of the track to provide a blanked space between the first and last recorded digit, a data comparing device associated with said storage medium and buffer storage device, means dependent upon reading of the first digit position recorded for initiating operation of said buffer storage means to deliver the stored data to said comparing means in timed relation with the recorded data, and means for initiating a second random recording operation of the same data on the same track if the buffer storage and recorded data do not agree.

2. In a device for storing words of data, each word including a plurality of digit positions recorded thereat to provide coded character representations, the combination of a rotatable storage medium having a plurality of spaced data storing tracks, each track including one or more words arranged serial by digit to provide a group of words and wherein a gap is provided between the first digit and the last digit position of each group, an intermediate storage unit for temporarily storing a group of words for delivery to a track, a transducer for reading,

erasing and writing on the tracks, means for selectively positioning said transducer at a desired track, means for erasing a predetermined length of the selected track to remove previously recorded data, said erasing operation occurring at random on the track without regard to the beginning of the previously located data, means for generating a signal at the end of the erasing operation for recording on the track, and means for delivering the group of words from said intermediate storage unit to said transducer serial by digit for storage on the track, said last digit recorded in the group overlapping into the erased portion of the track.

3. The combination as claimed in claim 2 wherein the recording of data at each track occurs in a random manner from track to track.

4. The combination as claimed in claim 2 including means responsive to the completion of the recording operation for initiating a checking operation for the recorded data, a digit comparing device, means for connecting the output from said temporary storage device and the selected transducer to said comparing device, means dependent upon the generated signal signifying the beginning of the record on the selected track for initiating operation of the temporary storage device to supply data therefrom to said comparing device digit by digit in timed relation with like digit positions delivered from said rotatable storage medium, and means responsive to recording errors indicated in said comparing device for initiating a second recording operation, whereby the entire contents of said temporary storage device is again recorded at random on the selected track.

5. In a device for storing data in digit positions to provide coded character representations, the combination of a rotatable random access storage medium having a plurality of spaced data storing tracks, each track being adapted to have recorded thereon a plurality of data bearing digits with a blanked space between the last and first recorded digit to provide an end of record indication, a transducer associated with said rotatable storage medium,

40 means for selectively positioning said transducer to a selected data bearing track, means for operating said transducer to initiate an erase operation beginning at random along the track, a buffer storage device for the data to be recorded, driving means for said buffer storage device to provide a serial by digit readout, means for delaying the delivery of the data for a predetermined number of digit positions, means for generating an end of space signal for recording on the track after the predetermined delay, and means for delivering the data from said buffer storage to said transducer after the predetermined delay for recording on the track serial by digit, at least the last digit overlapping a section of the previously erased portion of the track to provide a new end of record indication between the last and first digit stored in the track, 55 the circumferential location of the end of record indication varying from track to track and from recording to recording operation on the same track.

6. The combination as claimed in claim 5 including means responsive to an output from the last digit recorded 60 for terminating the recording operation, a write check control, means responsive to the termination of the recording operation for operating said write check control, a digit by digit comparing device, means for conditioning said comparing device from said write check control,

65 means for connecting the outputs from said buffer storage device and said random access disk storage unit to said comparing device, means dependent upon receiving the end of gap signal on the selected track for initiating the digit comparing operation, said end of gap signal 70 being responsive to operate said driving means for said buffer storage device, means for bypassing said delay means to immediately operate said drive means to deliver the data from said buffer storage device digit by digit in timed relation with like digit positions in said random access storage unit, and means responsive to a

correct recording of data for terminating the write check operation after the last recorded digit position has been compared.

7. The combination as claimed in claim 6 including means responsive to an error in the recorded data for automatically initiating a second complete recording operation of the data on the same track, said second and any subsequent recording occurring at random along the circumference of the track.

8. In a magnetic memory device for storing words of data, each including a plurality of digit positions recorded thereat to provide coded character representations, the combination of a plurality of rotatable disks having magnetizable surfaces on which data are recorded in a plurality of circular addressable tracks, a transducer for selectively reading, erasing or writing on a selected track, means for moving said transducer to any one of the tracks, a register for receiving the address of any of the tracks, means responsive to the values stored in said register for actuating said transducer moving means accordingly to position said transducer at the track corresponding to the address, a temporary storage device for retaining the data to be stored, means for initiating an erasing operation after said transducer is positioned at the selected track, said erasing operation occurring at random with respect to the previously recorded data on the selected track, and means for delivering the data in the temporary storage device to said transducer for recording on the selected track serial by digit after a predetermined number of previously recorded digit positions have been erased, at least the last bit recorded overlapping a section of the erased portion to provide a space between the beginning and ending of the recorded group of words.

9. The combination as claimed in claim 8 wherein consecutive recording on any selected track occurs at random with respect to the previously recorded data, and the random recording varies from track to track and disk to disk.

10. In a magnetic memory device for storing words of data, each including a plurality of digit positions recorded thereat to provide coded character representations, the combination of a plurality of rotatable disks having magnetizable surfaces to provide a plurality of spaced addressable data storing tracks, each track including storage for a plurality of words arranged serial by digit to provide a group of words and wherein a blanked space is provided between the beginning of the first word and the end of the last word in each group, a transducer for selectively reading, erasing and writing on any selected track, means for moving said transducer to any one of the tracks, a register for consecutively receiving and storing the addresses of any of the tracks, means responsive to the address delivered to said register for actuating said transducer moving means to position said transducer at the track corresponding to the address in

said register, an intermediate storage device for the data to be recorded, means for initiating an erasing operation for a predetermined number of words along the track to remove previously recorded data prior to the delivery of the data to be recorded, said erasing operation occurring at random on the track without regard to the beginning of the previously recorded data, means for generating and recording an end of space signal after a predetermined number of digit positions have been erased, and means for delivering the data to be recorded serial by digit to said transducer for recording on the track, at least a portion of the last digit in the delivered group overlapping an initially erased portion of the track.

11. A magnetic memory device comprising a plurality of spaced disks having a recording surface upon each side thereof, each disk having a plurality of data storing tracks on each face, means for rotating said disks in unison, a plurality of pairs of oppositely facing transducers disposed adjacent said disks and adapted to coat with any of said disks, one transducer on each side thereof for each disk, a calculator having a register, means for loading said register with an instruction to define a specific track on one of said disks, means dependent upon sampling the instruction in said register for shifting the selected pair of transducers to the disk and track specified by the instruction, means dependent upon the same instruction for selecting one of the pairs of transducers, a buffer storage device for a plurality of data bearing digit positions divided into words to provide a group of words to be recorded, means for initiating an erase operation on the selected track after the transducer has been positioned independently of any previously recorded data on the track, means for terminating the erasing operation after a predetermined number of words of data have been erased, means for initiating delivery of the data from said buffer storage device to the selected track, said delivery occurring parallel by bit and serial by digit and word, a translator for transferring the parallel delivered bits to serial for recording on the track serial by bit, digit and word, and a clock for gating the serial delivery of data to said transducer, at least the last bit of the last digit of the last delivered word overlapping a section of the previously erased portion of the track to provide an end of record space between the last and first digit of the recorded group, said space being provided at random with each recording on the same track, from track to track and disk to disk.
